UNITED STATES PATENT OFFICE

ERWIN C. HORTON, OF HAMBURG, AND HENRY HUEBER, OF BUFFALO, NEW YORK, AS
SIGNORS TO TRICO PRODUCTS CORPORATION, OF BUFFALO, NEW YORK

RESONATOR CONSTRUCTION

Application filed November 17, 1930. Serial No. 496,308.

This invention relates to devices for emitting warning notes or signals, and primarily to such devices of the horn type as are adapted for use on automobiles, boats and other vehicles.

The invention resides in the structural form and manner of formation of the trumpet or sound amplifying and directing portion of the horn, which is adapted to be used in connection with electric or fluid pressure sound generating mechanism and is particularly adapted for use in conjunction with such mechanism of the type disclosed in our co-pending application Serial No. 486,228, filed October 3, 1930, in which a sound generating valve is alternately drawn away from and pressed against a seat by the combined actions of suction and spring pressure. The trumpet structure contemplated by this invention is adapted to modify and direct the oscillations or sound waves induced in the air column therein by the sound generating mechanism. The trumpet parts are of light sheet material which may be readily stamped to shape thus permitting of very light weight and economical manufacture.

These and other objects and advantages will become apparent from the following description of a typical device embodying the principles of the invention, reference being made to the accompanying drawings wherein:

Fig. 1 is a side elevational view showing the trumpet of the present invention horn assembly; and

Fig. 2 is an enlarged perspective sectional view taken along line 2-2 of Fig. 1.

As shown in Fig. 1 the horn comprises a sound box or casing 10, which contains sound creating means which may be similar to those disclosed in our co-pending application hereinbefore referred to and which may be actuated by fluid of less-than-atmospheric pressure in the suction line 11. It is to be understood, however, that other sound generating means of the mechanical, electrical, or fluid pressure actuated types may be mounted in the casing 10. The latter has an open tubular portion 12 extending forwardly thereof, into which is pressed the small tubular end 13 of

the resonator or trumpet member designated generally at 14. The trumpet is formed of a pair of substantially similar but reversed sheet or plate stampings 15, each having a serpentine or S-shaped trough or corrugation 16 stamped therein. These deformations are preferably of semi-circular cross-section, increasing in radius from the small ends 13 to the opposite or enlarged trough ends 17.

The plates 15 are secured together as by welding or soldering, and the completed horn suitably mounted as by conveniently arranged holes 18 in the webs between the troughs 16. The plate deformations complement each other to form an S-shaped trumpet passage 19 of increasing diameter from the end 13 to the end 17. The passage is completely closed except at the ends thereof, each plate extending beyond the trough edges to provide comparatively wide flange or edge portions 21 for closely abutting similar edge portions of the other plate, thus sealing the passage 19, except at its ends, against the outside atmosphere. The reduced end 13 of the trumpet 14 is not provided with such flange portions 21, this end comprising only the deformed or trough-shaped portions 16 which together form a tubular extension of substantially circular cross-section.

A bell 22, preferably having a rolled edge 23 at its forward enlarged end, has its reduced end 24 pressed into or otherwise secured to the trumpet conduit end 17. This bell is preferably spun from a single sheet, although it may be stamped or otherwise formed from other material.

It will be understood that the trumpet parts 15 may be secured together by other means than welding, and that various means may be utilized for securing these parts to the bell 22 and sound box 10. It will further be understood that the structure described is merely exemplary of the principles of the invention and may be variously modified within the scope of the invention which is intended to be commensurate with the appended claims.

What is claimed is:

1. A horn comprising a sound box, a

- trumpet member having a tubular end portion engaging said sound box in telescoped relation, said trumpet comprising a pair of complementary sections each having a continuous deformation therein, said deformations together defining a continuous passage extending from said end portion to another portion of said trumpet member, and a bell attached in telescoped relationship to said trumpet member at said another portion thereof.
2. A trumpet member for a horn comprising a pair of plates having portions of their adjacent faces in contact, at least one of said plates having a continuous deformation therein, the material of said deformation cooperating with the adjacent portions of the other plate to define a continuous trumpet passage, said passage at one end being enlarged with respect to adjacent portions of the passage, a bell telescoped within the enlarged portion of the passage, the telescoped end of the bell being flush with said adjacent portions of the passage and providing a continuation of the trumpet passage.
3. A trumpet member for a horn comprising a pair of plates having portions of their adjacent faces in contact, said plates having deformations thereon cooperating to provide a trumpet passage, one end of said passage being enlarged and being separated from the adjacent portion of the passage by a shoulder, and a bell telescoped within said end of the passage and abutting said shoulder, the walls of said bell being of thickness corresponding to the depth of the shoulder to provide a continuous passage through the bell and plates.
4. In a trumpet for horns, a pair of plates disposed side by side, each of said plates having a continuous deformation of S-shaped terminating at opposite sides of the plates, said deformations cooperating to provide a continuous trumpet passage of S-shape having its ends opening at opposite sides of the plates.
5. A trumpet for horns comprising a pair of complementary plates each having a projection at one side thereof, said plates having complementary grooves formed therein to provide a sound passage opening at marginal portions of the plates, said grooves extending through the projections, whereby the latter complement each other to form a tubular extension from the body of the trumpet.
